UNITED STATES PATENT OFFICE.

CHARLES HENRY KRAUSE, OF SOUTHLAKE LINDEN, MICHIGAN.

STAMP-MACHINE.

SPECIFICATION forming part of Letters Patent No. 678,300, dated July 9, 1901.

Application filed October 22, 1900. Serial No. 33,894. (No model.)

To all whom it may concern:

Be it known that I, CHARLES HENRY KRAUSE, a citizen of the United States, and a resident of Southlake Linden, in the county of Houghton and State of Michigan, have invented a new and Improved Stamp-Machine, of which the following is a full, clear, and exact description.

This invention relates to improvements in atmospheric stamp machines or mills for ores or the like; and the object is to simplify the construction of this class of machine and particularly the machine shown in the patent granted to me under date of November 12, 1889, No. 414,910, and with other changes in construction I omit the fast and slow motion mechanism in said patent.

I will describe a stamp-machine embodying my invention and then point out the novel features in the appended claims.

Reference is to be had to the accompanying drawings, forming a part of this specification, in which similar characters of reference indicate corresponding parts in both figures.

Figure 1 is a partial section and partial elevation of a stamp-machine embodying my invention. Fig. 2 is a sectional detail showing the air-cylinders and pistons.

The frame of the machine comprises a base 1 and uprights 2, connected by cross-bars 3. Mounted on the foundation is a mortar 4, in which the pestle or shoe 5 operates, said pestle being attached to a stamp-rod 6. Supported in the frame are differential cylinders 7 and 8—that is, the cylinder 7 is of greater area or volume than the cylinder 8. By this construction a large volume of air in the cylinder 7 is forced into the cylinder 8 of less volume, thereby creating a great pressure on

the piston 9, operating in said cylinder 8 and attached to the rod 6. Operating in the cylinder 7 is a piston 10, the connecting-rod 11 of which is attached to a crank on a crank-shaft 12, that may be rotated by any desired means.

Arranged within the valve-casing 13, which communicates with the upper cylinder 7, are valves 14 and 15, the valve 14 being operated by movements of the machine, while the valve 15 is automatically opened by air-pressure.

A valve-casing 16 communicates with the cylinder 8, and arranged in this casing is a

spring-pressed upwardly-opening valve 17. The valve 14 has a rod connection 18 with a lever 19, pivotally connected to one of the uprights 2, and as a means for adjusting the throw of said valve 14 the rod 18 is made in two sections, connected by a turn-buckle or the like 20. The lever 19 is designed to be raised at its free end to open the valve 14 by means of a tappet 21 on the rod 6. This tappet is made in the form of a pulley to receive a band for imparting a slow rotary movement to said rod.

In operation the piston 10, moving upward, produces between the two pistons a partial vacuum that causes the lower piston to rise, consequently raising the pestle 5 until the tappet 21 comes in contact with the lever 19. Then by continued movement the valve 14 is opened, allowing atmospheric air to pass in, raising the valve 15, and rushing in between the two pistons. The valve 15 will close just as soon as pressure is restored in the cylinder; but the valve 14 will not close until the stamp-shaft is moved down to the place at which it opened. Therefore this valve is automatic. As the upper piston 10 moves downward a great pressure is produced, driving the lower piston down with great force and producing a heavy blow of the stamping device. An air-cushion between the pistons, however, will permit the pestle or stamping device to accommodate itself to the amount of material in the mortar. After the lower piston passes the port leading into the valve-casing 16 the air-pressure is automatically exhausted through said valve-casing, the pressure, of course, opening the valve 17, and this valve is closed by the outer atmospheric pressure after the inner air shall have been exhausted.

I have shown a projection or boss 22 on the lower side of the upper piston 10, the object of which is to produce a greater displacement when a more forcible blow of the stamp is desired, and this boss may be made of any size to suit required conditions. I do not confine myself, however, to this construction, as the lower side of said piston may be in one plane surface. The length of the stroke of the upper piston may be the same as the lower piston or may be less; also, the ratio of the cylinders may be any quantity.

Having thus described my invention, I claim as new and desire to secure by Letters Patent—

- 5 1. In a stamp machine or mill, two differential cylinders arranged one above the other, a piston operating in the smaller cylinder, a stamping device carried by said piston, a valve for controlling the exhaust from the smaller cylinder, a piston in the larger cylinder and unconnected with the smaller piston, means for operating the piston in the larger cylinder, a valve-casing communicating with both the cylinders, an inlet-controlling valve in said casing, a lever with which said valve 15 connects, a tappet carried by the stem of the smaller piston for engaging with said lever to open the valve, and an air-pressure-actuated valve also in said casing, substantially as specified.
- 20 2. A stamp machine or mill, comprising dif-

ferential communicating cylinders one above the other, a piston operating in the smaller cylinder, a stamping device carried by said piston, a pressure-actuated valve controlling the exhaust from said lower cylinder, a piston in the larger cylinder, means for operating said piston in the larger cylinder, a valve-casing communicating with the cylinders, an inlet-controlling valve in said casing actuated by a movement of the lower piston, and 25 an air-pressure-actuated valve also in said casing, substantially as specified.

In testimony whereof I have signed my name to this specification in the presence of two subscribing witnesses.

CHARLES HENRY KRAUSE.
